[57] **CLAIM**

The ornamental design for a baseball glove web, as shown and described.

DESCRIPTION

FIG. 1 is a front, top and side perspective view of a baseball glove web showing my new design;

FIG. 2 is a front elevational view thereof, the opposite side being a mirror image;

FIG. 3 is a right side elevational view thereof;

FIG. 4 is a left side elevational view thereof;

FIG. 5 is a top plan view thereof; and,

FIG. 6 is a bottom plan view thereof.

The mitt shown in broken lines in FIG. 1 is for illustrative purposes only and forms no part of the claimed design.
